CLAIM

The ornamental design for a floor mat or similar article,
as shown and described.

DESCRIPTION

FIG. 1 is a top perspective view of a floor mat or similar
article showing my new design;

FIG. 2 is a top plan view thereof;

FIG. 3 is an elevational view of one side thereof, the
other sides being identical thereto; and,
FIG. 4 is a bottom plan view thereof.

The drawing views have been broken away to indicate
indeterminate size.
